CLAIM

The ornamental design for a gel seat cushion, as shown and described.

DESCRIPTION

FIG. 1 is a top perspective view of a gel seat cushion, showing my new design.

FIG. 2 is a bottom perspective view thereof.

FIG. 3 is a front view thereof.

FIG. 4 is a rear view thereof.

FIG. 5 is a right side view thereof.

FIG. 6 is a left side view thereof.

FIG. 7 is a top view thereof.

FIG. 8 is a bottom view thereof.

FIG. 9 is an enlarged view of the selected portion in FIG. 1; and,

FIG. 10 is an enlarged view of the selected portion in FIG. 2.

The dash dot dash lines in FIGS. 1, 2, 9 and 10 are for the purpose of illustrating the enlarged view indicators and form no part of the claimed design.
